UNITED STATES PATENT OFFICE.

JAMES S. LESTER, OF ATLANTA, GEORGIA.

FAUCET.

SPECIFICATION forming part of Letters Patent No. 542,201, dated July 2, 1895.

Application filed December 20, 1894. Serial No. 532,444. (No model.)

To all whom it may concern:

Be it known that I, JAMES S. LESTER, a citizen of the United States, residing at Atlanta, in the county of Fulton and State of Georgia, have invented a new and useful Faucet, of which the following is a specification.

My invention relates to faucets for use in connection with water-service pipes, soda-water fountains, &c., and the objects in view are to provide a faucet which is adapted to close automatically by the pressure of the fluid in the pipe or vessel to which it is connected; to provide means for insuring the proper seating of the valve; to provide means whereby the surface of the valve which is exposed to the pressure of the fluid is increased without increasing the area of the valve; to provide means whereby the dust or gravel which passes to the seat of the valve is exposed to a flow of liquid and is thereby displaced, and to provide means whereby the valve is cushioned as it closes to prevent jarring and rattling in the service-pipe.

Further objects and advantages of the invention will appear in the following description, and the novel features thereof will be particularly pointed out in the appended claim.

In the drawings, Figure 1 is a perspective view of a faucet constructed in accordance with my invention, the same being applied to an ordinary elbow coupling or joint. Fig. 2 is a vertical central section of the same. Fig. 3 is a vertical section on the line 3 3 of Fig. 2. Fig. 4 is a vertical central section of a slightly modified form of faucet attached to an ornamental elbow joint or coupling.

Similar numerals of reference indicate corresponding parts in all the figures of the drawings.

The shell 1 of the faucet comprises a lower tubular passage 2 and an upper enlarged chamber 3, the shoulder between said parts being constructed to form a downwardly-tapered or conical valve-seat 4, around which, and resting upon the flat portion 5 of the shoulder, is arranged a washer 6 of rubber, leather, or other slightly-compressible material. The valve-head 7 is slightly convexed upon said under surface and is adapted to rest upon the upper surface of the washer, and is provided with a central depending down-

wardly-tapered or conical enlargement 8, which forms a centering-guide to adjust the valve-head as it descends and cause it to approach its seat squarely. The valve-stem 9 depends from the center of said conical enlargement or centering-guide and is loosely connected within the tubular passage to a transverse pin 10, which extends through and operates in vertical slots 11 in the sides of the shell, a collar 12 being fitted to slide exteriorly upon the reduced or lower portion of the shell and the extremities of said pin being fitted in perforations in said collar and secured at one end by means of a head 13 and at the other end by means of a nut 14.

At the front of the shell is formed a boss 15, to which is fulcrumed a bifurcated lever 16, having a finger-rest 17, the arms 18 formed by said bifurcation being extended in opposite direction around the shell to diametrically opposite points, and being connected by means of links 19 with the ends of the pin to which the valve-stem is attached. The collar covers the slots in the sides of the shell, and the links which are interposed between the lever and the pin allow said parts to move freely, the former around its fulcrum as a center and the latter in the vertical guide-slots in which it is fitted.

Interposed between the lower side of the valve-head and an interior annular shoulder 20 in the shell, and coiled around the stem of the valve, is a cushion-spring 21, the tension of which is sufficient to prevent jarring as the valve comes to its seat after the removal of pressure upon the lever, but is insufficient to resist the pressure of the liquid upon the upper surface of the valve.

The upper surface of the valve head or disk is concaved to increase the surface for the pressure of the liquid without increasing the horizontal area of the valve, thereby forming a cup 22, which performs the additional function of catching impurities and sediment of a solid nature which may enter the faucet, and thus protects the valve-seat; and the enlarged chamber in which the valve operates is bulged or constructed in a partially spherical form, whereby the annular passage between the periphery of the valve and the interior surface of the chamber is enlarged as the valve ascends from its seat; but when the valve is at

the limit of its upward movement the area of the said annular passage is equal to the cross-sectional area of the lower portion or passage 2.

At the inner end of the finger-rest which 5 forms a part of the operating-lever of the valve is an upturned ear 23, which, when the valve is in its closed position, is approximately in contact with the surface of the shell, and when it is desired to hold the valve 10 partially or wholly open to allow a continuous flow of liquid, as in filling a bath-tub, or for any other analogous purpose, a small object 24, such as a toothpick, (shown in the drawings, Fig. 1,) should be inserted between 15 the ear and the contiguous portion of the shell. This interposed object 24 should be tapered, as shown, in order that it may be inserted more or less to vary the extent of opening of the valve; and while I have shown and 20 mentioned a tooth-pick as a convenient object it will be understood that any other tapered pin or other article may be employed. It is my object to provide means whereby in special cases the valve may be held wholly or partially 25 open, and at the same time provide a construction whereby unless there is a special object in view and unless special provision is made, the valve will close automatically and will be held in its closed position 30 by the pressure of the fluid in the service-pipe. When the lever is released the valve closes, and if it is desired to have a continuous flow a suitable object must be inserted between the upturned ear of the lever and the shell, 35 and such object does not form a part of the faucet, and hence it is the presumption that the valve will not be locked in its open position, except when the object in view is sufficiently important to justify such action.

40 In Fig. 4 I have shown a modified form of the faucet in which it is applied to an ornamental elbow joint or coupling 25, which serves as a support for a bucket, the shell being substantially the same construction as 45 that above described, and the valve-seat, washer, and valve being of similar arrangement, construction, and operation. The means for operating the valve differ from that above described in that the operating-lever 50 is fulcrumed in a slot 27 in the side of the reduced portion of the shell and is provided with a flat arm 28, which fits in a slot 29 in the lower end of the valve-stem 30. The upper edge of said reduced arm is cut away to 55 form an arc-shaped seat 31, which bears against a convex shoulder at the upper end of said slot in the valve-stem. The portion of the shell contiguous to the slot in which the operating-lever is fulcrumed is enlarged 60 to form a boss 32, the outer side of which is convexed concentric with the fulcrum-pin 33, and the lever is provided with a contiguous concaved shoulder 34, also concentric with its fulcrum, which operates in contact with said 65 convex surface and thus forms a break-joint. An ear 35 is formed on the lever contiguous

to an abrupt shoulder 36 on the shell, whereby a tapered object may be inserted to hold the valve in its open position, as above described, in connection with the preferred form of faucet. The cushion-spring 37 corresponds in construction and function with that above explained.

From the above description it will be seen that the improved faucet is adapted to be 75 closed and held in such position by the weight or pressure of the liquid in the service-pipe, that said valve cannot be left open accidentally, that means are provided for guiding the valve to its seat, and that a cushion is arranged 80 to relieve the shock or jar in the pipe when the valve closes, and in addition to the above it should be understood that the object in forming a loose connection between the valve-stem and the lever, such loose connection providing for a lateral vibration or movement of the lower end of the stem, is to allow the valve to assume an inclined position when a gravel or small hard object comes between the valve-seat and the valve. This inclination of the 90 valve relieves the foreign object from a portion of the pressure which otherwise would be brought to bear upon it, and thus provides for the removal of the object by the force of the liquid in the pipe. The portion of the 95 elbow joint or coupling which is introduced into the enlarged chamber of the faucet is thickened, as shown at 38, whereby it lies in the path of the valve-head to prevent the valve from being thrown above the point necessary to properly open the passage. This 100 construction is of especial advantage, in connection with the form of faucet, which is shown in Fig. 4, wherein no positive connection between the operating-lever and the valve-stem 105 is provided. A further advantage of this contraction of the throat of the joint or coupling resides in the fact that it condenses the stream of water or other liquid as it enters the chamber of the faucet and centers the 110 same upon the concave or cup-shaped upper surface of the valve-head, thus adding to the efficiency of the liquid as a means of closing and maintaining in its closed position the valve.

115 It is obvious that in practice various changes in the form, proportion, and the minor details of construction may be resorted to without departing from the spirit or sacrificing any of the advantages of this invention.

Having described my invention, I claim—

A faucet having a coupling, a casing secured to the outlet end of the coupling and provided with a valve-seat arranged contiguous to the extremity of the coupling, a valve mounted 125 to operate between the seat and the extremity of the coupling and of greater area than the outlet opening of the latter, the upper surface of the valve being concaved, a cushion spring opposed to the movement of the valve 130 in approaching its seat and insufficient in strength to resist the pressure of the fluid,

whereby the spring is compressed as the valve is returned to its seat, means for moving the valve from its seat against the pressure of the fluid, and loose connections between said means and the valve-stem, substantially as specified.

In testimony that I claim the foregoing as

my own I have hereto affixed my signature in the presence of two witnesses.

JAMES S. LESTER.
